(57) **CLAIM**

The ornamental design for a safety harness for restraining a child in a car carrier, as shown.

DESCRIPTION

FIG. 1 is a front elevation view of the preferred design of a harness/restraint system for a child car carrier showing my new design;

FIG. 2 is a rear elevational view thereof; and,

FIG. 3 is the left side elevational view thereof which is a mirror image of the right side thereof.

1 Claim, 1 Drawing Sheet

FIG. 3

FIG. 2

FIG. 1
